UNITED STATES PATENT OFFICE

BRYAN Y. CUMMINGS, JR., OF SPRINGFIELD, MISSOURI

RADIO RECEIVING APPARATUS

Application filed April 11, 1928. Serial No. 269,146.

My invention relates broadly to radio receiving apparatus and more particularly to a simplified construction of radio receiver employing an electron tube circuit requiring 5 minimum power consumption for reproduction of signals at relatively large volume.

One of the objects of my invention is to provide a circuit arrangement for a radio receiving apparatus in which a single electron 10 tube system may function as a regenerative circuit for the reproduction of signaling energy at relatively large volume with minimum power consumption.

Another object of my invention resides in 15 the provision of an impedance in the input circuit of an electron tube system cooperating with the impedance of the telephone headset or loud speaker in the output circuit of the electron tube system and with a capacity 20 coupling circuit for facilitating the transfer of energy between the input and output circuits of the electron tube system for regenerative operation of the electron tube system.

25 Still another object of my invention resides in the circuit arrangement for an electron tube system where losses in the electron tube system are minimized and the available signaling energy utilized to the maximum degree for the reproduction of signaling energy 30 at relatively large volume in a single electron tube circuit.

Other and further objects of my invention reside in the arrangement described more 35 clearly in the specification hereinafter following and set forth in detail in the accompanying drawing.

In the circuit arrangement of my invention the receiving circuit is greatly simplified 40 by utilizing a single electron tube in conjunction with a tuned circuit for regenerative operation without the usual high potential source in the plate circuit. I make use of the impedance of the telephones in the circuit 45 as a primary impedance of a system for transferring energy from the output circuit to the input circuit and introduce a secondary impedance in the grid circuit of the electron tube system and then interconnect the 50 two impedances by means of a radio fre-

quency by-pass and an audio frequency coupling condenser. I arrange a source of low potential for heating the cathode of the electron tube and provide a variable resistance in circuit with the cathode and source of potential, across which a sufficient drop is produced for operating the plate circuit of the electron tube.

Referring to the drawing in more detail, reference character 1 designates the antenna 55 which is conductively coupled to the grid inductance 4 at a point 16, counting from the grounded end 17 of the grid inductance, that will put one-fourth of the inductance in the antenna circuit. Inductance 4 is tuned by a 60 variable condenser 5. When the capacity of 5 is increased, the wave-length of the antenna circuit is increased at the same time the wave-length of the grid circuit is increased, resulting in a louder signal on the higher wave- 65 lengths because of closer resonance between the two circuits.

Reference character 3 represents a coil of 70 higher inductance than is ordinarily used to produce regeneration, and which produces 75 the regenerative feedback to the grid circuit of tube 11. This inductance 3 in the plate circuit of tube 9 has to be higher than usual because of the low plate voltage.

The filament battery 8 is one of approximately 80 four and a half volts and is a standard battery known by its common use in radio receiving circuits as a "C" battery. This battery not only supplies the filament current for filament electrode 10 but the plate and 85 grid current as well, the plate current being derived from the drop voltage across the variable filament resistance 7. The tube 9 is represented as having a grid 11 and a plate 12.

Reference character 14 refers to the telephones, and may in actual practice be either 90 telephone receivers or a loud speaker. The device 14 performs the dual duty of reproducing the audible signals and forming the primary of a double impedance reflex audio 95 frequency amplifier.

The condenser 15 connects between one side of the winding of the sound reproducer 14 and a point between the reactance 6 and the tuned circuit 4-5. The condenser 15 is posi- 100

tioned between that end of the reactance 6 which is remote from the cathode 10 and the side of the sound reproducer winding of the device 14 which is remote from the cathode 10.

5 Reference character 6 designates the high impedance choke for passing audio frequency currents and forms the secondary of the double impedance reflex audio frequency amplifier, and also serves as a grid leak. The value 10 of this impedance as a grid leak is low, but is sufficient in this circuit because of low plate voltage and makes the grid circuit perfectly stable in operation.

15 A further improvement offered by the use of the telephones in my circuit arrangement is that there are no extra losses in the plate circuit due to the presence of the primary of an audio frequency transformer as would ordinarily be used in a reflex circuit. All of the 20 audio frequency impedance in the plate circuit performs the useful duty of reproducing the audible signals.

25 In the circuit arrangement of my invention the telephones serve the dual purpose of reproducing the sound at the same time that the telephones serve as a primary impedance of the double impedance audio frequency reflex amplifier circuit thereby reducing electrical losses in the system and enabling 30 reproduction of substantial volume from a single electron tube system.

35 The circuit arrangement of my invention has produced extremely efficient results in practice, and while I have described a particular embodiment of my invention, I desire that it be understood that modifications may be made and that no limitations upon my invention are intended other than those imposed by the scope of the appended claims.

40 What I claim as new and desire to secure by Letters Patent of the United States is as follows:

45 1. A radio receiving system comprising an electron tube having grid, cathode and plate electrodes, a tuned input circuit interconnecting said grid and cathode electrodes, an output circuit interconnecting said plate and cathode electrodes, a cathode heating circuit including a source of potential and a variable resistor connected in series with said cathode electrode, sound reproducer windings disposed in said output circuit, a connection from one side of said sound reproducer windings to said plate electrode, a connection from 50 the other side of said sound reproducer windings to a point on said resistor, a reactance included between said tuned input circuit and said cathode electrode, and a condenser interconnecting the end of said reactance remote from said cathode with the side of said sound reproducer windings remote from said cathode electrode.

55 2. A radio receiving system comprising an electron tube having a grid, cathode and plate electrodes, a tuned input circuit intercon-

necting said grid and cathode electrodes, an output circuit interconnecting said plate and cathode electrodes, means regeneratively coupling said input and output circuits, a cathode heating circuit including a variable resistance and a source of potential in series, sound reproducer windings disposed in said output circuit, a connection between the positive side of said source and one side of said sound reproducer windings, a connection between the other side of said sound reproducer windings and said plate electrode, a reactance disposed between said tuned input circuit and said cathode electrode, and a condenser interconnected between an intermediate point in said tuned input circuit and said reactance and that side of said sound reproducer windings remote from said cathode electrode.

60 In testimony whereof I affix my signature. 85
